United States Patent Office

Des. 222,248
Patented Oct. 12, 1971

222,248

CHAIR FRAME

Gardner Leaver, New York, N.Y., assignor to
Steelcase Inc., Grand Rapids, Mich.

Original design application Mar. 20, 1969, Ser. No. 16,351.
Divided and this application May 7, 1970, Ser. No.
22,873

Term of patent 14 years

Int. Cl. D6—06

U.S. Cl. D15—1

FIG. 1

FIG. 2

FIG. 3

FIG. 4

FIG. 6

FIG. 5

FIG. 1 is a perspective view of the chair frame;
FIG. 2 is a front perspective view of the chair frame;
FIG. 3 is a side view of the chair frame;
FIG. 4 is a rear perspective view of the chair frame;
FIG. 5 is a plan view of the chair frame; and,
FIG. 6 is a lower perspective view of the chair frame.
The novel and characteristic features of the design are
embodied particularly in that portion of the frame dis-
posed above the base.

I claim:

The ornamental design for a chair frame, substantially
as shown and described.
